ELECTRODE HOLDER

Frank J. Malnar, Euclid, Ohio

Application October 1, 1942, Serial No. 460,365

10 Claims. (Cl. 219—8)

This invention relates generally to the art of electric welding and more particularly to a new and improved electrode holder.

In the drawings accompanying and forming a part of this specification,

Figure 1 is a top plan view, partly in section, of one form of holder embodying the present invention and showing the manner of placing an electrode in and removing it from the holder;

Figure 2 is an end view of the device of Fig. 1, 10 the electrode of that figure being omitted;

Figure 3 is a fragmentary, side elevational view, partly in section, showing another embodiment of the present invention;

Figures 4 and 5 are, respectively, an end view 15 and a cross-sectional view taken on line 5—5 of the device shown in Fig. 3;

Figures 6 and 7 are, respectively, a longitudinal, central cross-sectional view and an end-view of another embodiment of the present invention;

Figures 8 and 9 are, respectively, side elevational and end views of another modified embodiment of the invention.

Figures 10 and 11 are, respectively, a side elevational view, partly in section, and an end view 25 of another modified embodiment of the invention.

Figure 12 is a fragmentary, side elevational view, partly in section, of another embodiment of the invention; and,

Figure 13 is an end view of the device of Figure 12.

The electrode holder shown in Figs. 1 and 2 consists of a hollow, electrically non-conducting handle 1, which is rectangular in cross-section and in one end of which is disposed a hollow metal member 2 which is rectangular in cross-section and has a fairly close fit against the inner surfaces of handle 1. A cable 3, from a source of suitable welding current, is attached to metal member 2 in any convenient manner, as by bolt 4 and nut 5, the head of the bolt 4 being surrounded by a bushing 6 of electrical insulating material which can be attached to the head of bolt 4 as by a pin 6a passing thru a hole in the bolthead. This bushing prevents arcing between the head of the bolt 4 and any other outside metal member.

The metal member 2 supports a plurality of metal rods 7 secured thereto at the ends, as by welding. These rods project in parallelism beyond the ends of the handle 1 and member 2 and are arranged triangularly, that is, at the corners of an imaginary triangle, and are spaced apart from each other. When an electrode is as-

sembled with these rods with one rod on one side of the electrode and two rods on the other side thereof, the electrode springs the rods apart and the rods exert sufficient spring tension on the electrode to retain it in any position desired by the welder.

Fig. 1 shows the electrode 8 in full line position when the device is ready for welding and also shows, in the dotted line position, the first step of assembling an electrode with the rods 7. To assemble the electrode with the rods the welder places the electrode in substantially the dotted line position between two of the rods, and then uses the electrode to pry those rods apart far enough to permit the electrode to be swung into position between one of the rods and the third rod. Then the electrode may be adjusted to the desired angularity by swinging the electrode and will be held in that position by the spring tension of the rods. Similarly, the electrode may be removed from the holder by swinging it so that it clears one of the two rods on one side thereof, whereupon it is released from the rods and may be removed. It will be noted that the insulation 9 on electrode 8 does not prevent contact of the electrode with all the rods 7 but on the contrary the bare electrode does contact at least one current-carrying rod 7.

In Figs. 3, 4 and 5 the handle is round and is 30 preferably composed of wood or similar electrically non-conductive material. The handle 11 is provided with an axial hole 12 extending from the rear end thereof to, and intersecting with, a diametrical hole 13. A cable 14 in axial hole 12 extends to hole 13 where it is secured by bolt 15 and nut 16 against the two elongated electrode holding rods 17. These rods extend from one side of hole 13 thru the end of the handle 11 and to a point some distance therebeyond. The third rod 17a extends from within the end of the handle and is held in position by any suitable means, as by pin 18, which extends thru the handle and rod 17a. A furrul 19 serves to prevent splitting of the handle.

An electrode may be assembled between rods 17 on one side and 17a on the other side in the same manner as has been described with respect to the device of Fig. 1. It will be noted that the bolt 15 requires no insulation to prevent arcing 50 because it is housed within the confines of handle 11 and, therefore, cannot come into contact with any outside part.

In Figs. 6 and 7 the handle 21, the metal member 22, the cable 23, the bolt 24, nut 25 and insulating cap 26, and two electrode holding rods

27 are substantially like the corresponding parts in the apparatus of Figs. 1 and 2. The third rod 27a, instead of being welded to member 22 as in Fig. 1, is mounted on a pivot pin 28 and within member 22, is bent toward the center thereof as 5 at 27b, and then outwardly to project thru aligned openings in members 21 and 22, finally terminating in portion 27c which may be engaged by the welder's thumb. Within member 22 is disposed spring means engageable with portion 27b of rod 27a to pivot the rod about pin 28 and urge the outer end thereof toward rods 27 to grip an electrode therebetween. This spring means, as shown, comprises a leaf spring 29, which is seated at its sides in opposite corners of member 22 and may be welded in place. This spring member 29 has a forward portion 29a shaped to bear against the bent portion 27b of rod 27a and coil spring 30 is compressed between this portion 29a and the adjacent inner surface of member 22. Spring 10 means 29 and 30 thus serve to pivot the rod 27a about pin 28, urging the outer end thereof towards rods 27 and the portion 27c away from the handle 21. It will be understood by those skilled in the art that the spring 30 may be dispensed with if desired, and also that the body portion of member 29 may be omitted if desired.

In Figs. 8 and 9 is shown a slight modification of the device of Figs. 1 and 2. In Figs. 8 and 9 the metal member 2 has four rods 7 welded in the inside corners thereof and any three of these four rectangularly positioned rods 7 may be used to grip an electrode after the manner shown in Figs. 1 and 2 and described hereinabove. With four rods 7 the electrode may be assembled in more different positions than is the case when only three rods are present.

In Figs. 10 and 11 is shown a further modification of the device of Figs. 1 and 2. In Figs. 10 and 11 the straight single rods 7 of Figs. 1 and 2 have been replaced by longer rods which have been bent into U-shape with the U portions being disposed in member 2 and welded thereto. As shown in Figs. 10 and 11, one of these U-shaped members, 37, is disposed in a plane at right angles to the other one.

In Figs. 12 and 13 hollow handle 41 is round and contains a round metal member 42 which is attached to a cable 3 by bolt 4 and nut 5, the head of the latter being provided with an insulating sleeve 6 held in place by pin 6a extending thru the sleeve and bolthead. The rods 41 are welded to the inner surface of member 42 and are arranged more or less rectangularly so that any three of the rods may be used to grip an electrode after the manner hereinabove described.

It will be obvious that any of the hollow metal members 2 and 42 may be made solid at their rod carrying ends and recesses may be provided on their outer surfaces in which the electrode holding rods may be placed and attached either by welding or in any other suitable manner.

While the electrode holding members of the several herein described embodiments of the invention are shown as being circular in cross-section, it will be understood that they may have different cross-sectional shapes. These rods may be triangular, rectangular or polygonal in cross-section.

It will be obvious to those skilled in the art that electrode holders embodying the present invention are simple in construction, and afford an efficient, positive means for holding an electrode which may be quickly and easily assembled therewith or disassembled therefrom.

Altho several different modifications of the present invention may have been shown and described herein, many others may be made. Accordingly, I do not limit my invention to the modifications specifically described but, on the contrary, include all modifications which fall within the appended claims.

Having thus described the invention so that others skilled in the art may be able to understand and practice the same, I state that what I desire to secure by Letters Patent is defined in what is claimed.

What is claimed is:

1. An electrode holder comprising a plurality of parallel metal rods supported at one end, said rods being spaced apart from each other throughout their full lengths and so arranged that an electrode may be held between two of said rods on one side thereof and one rod on the other side thereof by spring pressure, and means for conducting electric current to at least one of said rods.

2. An electrode holder comprising a hollow, electrically non-conductive handle, a plurality of metal rods mounted at one end of said handle and projecting in parallelism therebeyond, said rods being spaced apart from each other throughout their lengths and being so arranged that an electrode may be held between two of said rods on one side thereof and one of said rods on the other side thereby by spring tension of the rods, and means within said handle for conducting electric current to at least one of said rods.

3. An electrode holder, including a hollow, electrically non-conductive handle, a metal member in said handle and to which a source of electric current may be connected, a plurality of metal rods secured to said member near one end thereof and projecting in parallelism beyond the ends of said handle and member, said rods being spaced apart from each other throughout their lengths and being so arranged that an electrode may be held between two of said rods on one side thereof and one of said rods on the other side thereof by spring tension of the rods.

4. An electrode holder, including a hollow, electrically non-conductive handle, a metal member in said handle and to which a source of electric current may be connected, at least three metal rods having their ends secured to said member near one end thereof and projecting in parallelism beyond the ends of said handle and member, said rods being spaced apart from each other and arranged triangularly so that an electrode may be held between two of said rods on one side thereof and one of said rods on the other side thereof by spring tension of the rods.

5. An electrode holder, including a hollow, electrically non-conductive handle, a metal member in said handle and to which a source of electric current may be connected, four metal rods having their ends secured to said member near one end thereof and projecting in parallelism beyond the ends of said handle and member, said rods being spaced apart from each other and arranged rectangularly so that an electrode may be held between two of said rods on one side thereof and one of said rods on the other side thereof by spring tension of the rods.

6. An electrode holder, including a hollow, electrically non-conductive handle, a hollow metal member housed within said handle and to the inner surface of which a source of electric current may be connected, a plurality of metal

rods having their ends secured to the inner surface of said member near one end thereof and projecting beyond the ends of said handle and member, said rods being spaced apart from each other throughout their lengths and being so arranged that an electrode may be held between two of said rods on one side thereof and one of said rods on the other side thereof by spring tension of said rods.

7. An electrode holder, including a hollow, electrically non-conductive handle round in cross-section, a hollow metal member round in cross-section in said handle and to the inner surface of which a source of electric current may be connected, a plurality of metal rods having their ends secured to the inner surface of said member near one end thereof and projecting beyond the ends of said handle and member, said rods being spaced apart from each other throughout their lengths and being so arranged that an electrode may be held between two of said rods on one side thereof and one of said rods on the other side thereof by spring tension of said rods.

8. An electrode holder, including a hollow, electrically non-conductive handle rectangular in cross-section, a hollow metal member rectangular in cross-section in said handle and to the inner surface of which a source of electric current may be connected, a plurality of metal rods having their ends secured to the inner surface corners of said member near one end thereof and projecting beyond the ends of said handle and member, said rods being spaced apart from each other throughout their lengths and so arranged

that an electrode may be held between two of said rods on one side thereof and one of said rods on the other side thereof by spring tension of said rods.

- 5 9. An electrode holder comprising a hollow, electrically non-conductive handle, a plurality of metal rods mounted out of contact with each other at one end of said handle and projecting in parallelism therebeyond, one of said rods being 10 mounted for pivotal movement, said pivoted rod being bent toward the center of said handle and then projecting laterally thru the wall thereof, spring means within said handle for urging the free end of said pivoted rod toward the other, 15 fixed rods, and means within the handle for conducting electric current to at least one of said fixed rods.
10. An electrode holder comprising a tubular handle of insulating material; a conductor extending into one end of said handle; a cluster of not less than three closely grouped and independently flexible metallic spring rods; a metallic socket member within which one end of each of said rods is rigidly secured, said socket member being rigidly fixed in position within the opposite end of said handle with said cluster axially aligned and parallel with the axis of said handle, and means electrically connecting said conductor and said socket member, the outer free end portions of said rods being adapted to receive between them and to grip an electrode intermediate the ends of the latter.
